FIG. 1 is a front, and top side perspective view of a stator of vehicle alternator showing our new design;

FIG. 2 is a front elevational view thereof, the rear, the left side and the right side elevational views being the same image thereof; and,

FIG. 3 is a top plan view thereof, the bottom plan view being the same image thereof.

The broken lines in the figures are for illustrative purposes only and form no part of the claimed design.
